WILLIAM B. SMITH, OF ABERDEEN, INDIANA.

Letters Patent No. 66,404, dated July 2, 1867.

IMPROVEMENT IN BALING-PRESS.

The Schedule referred to in these Letters Patent and making part of the same.

TO ALL WHOM IT MAY CONCERN.

Be it known that I, WILLIAM B. SMITH, of Aberdeen, in the county of Ohio, and State of Indiana, have invented a new and improved Baling-Press; and I do hereby declare that the following is a full, clear, and exact description thereof, which will enable those skilled in the art to make and use the same, reference being had to the accompanying drawings, forming part of this specification, in which—

Figure 1 represents a plan or top view of my improved baling-press.

Figure 2, a sectional elevation, the plane of section being indicated by the line *x x*, fig. 1.

Figure 3 is a horizontal section taken through the line *y y*, fig. 2.

Figure 4 is a portion of a side elevation partly in section.

Figure 5 is a horizontal section taken through the line *z z*, fig. 2.

Similar letters of reference indicate corresponding parts.

This invention relates to a baling-press of that class in which the hay, cotton, or other article to be baled is held in place by a follower while it is being operated upon by a beater, both the follower and beater moving in a horizontal direction. The invention consists, first, in a new device for operating and releasing the follower; second, in a new arrangement for operating the beater, which is done by attaching the beater to a weighted rocking-frame and winding a rope attached to the said frame around a capstan, whereby the beater is drawn from the hay. By a certain device the frame is then released from the capstan and the weight on the frame drives the beater vehemently against the hay. Finally my invention consists in the aforesaid device for releasing the rocking-frame from the capstan.

The press A, which consists of the follower B, the beater C, the stationary side walls D and D', and the cover E, is firmly secured to a wooden bed-piece, F. Access to the press is had through the doors e in the cover and d in the side D. Through these doors the hay, cotton, hemp, or other article which is to be baled is placed within the press. The follower B is connected to a long lever, G, by links b b. The lever G swings on the pin g, as seen in fig. 1. To the other end of the lever are attached the ropes g¹ and g². The rope g¹ is secured to the lever by means of staples, or other devices, and is then passed over a pulley, f, at the rear, and is then attached to a drum, f¹, which plays loosely around the shaft of the capstan H. The rope g¹, as is thus seen, will, when wound around the drum f¹, draw the follower B back from the hay, while the rope g², which is attached to the bed-plate F in front of the lever, and passed over a pulley, g³, on the lever, and wound around a drum, f², on the capstan, will, when wound up, press the follower against the hay. The drums f¹ and f², both of which play loose around the shaft of the capstan, are operated only when thrown in gear with the windlass h by means of a clutch, h'. The drums f¹ and f² are provided with flanges at their top and bottom, and their respective bottom and top flanges are made in the shape of cams, as seen in fig. 3. The clutch h', when brought into contact with either of these cams, throws the drum, of which the cam is part, into gear, whereby the follower is operated in the desired direction. The beater C is connected by means of a link, c, to the triangular rocking-frame I. The latter swings on pins i, and is held by them to the stationary frame K. A rope, i', which is attached to the upper swinging end of the rocking-frame, passes over pulleys i'', and is then attached to a collar, l, which plays loosely around the upper part of the capstan H. The collar l is provided with a small projection, l', and is operated by a catch or pawl, k, which is pivoted to a flange, K', of the capstan. This catch is heaviest below its fulcrum, so that it will always hang down vertically by its own accord. When the capstan is turned by the power applied to the lever L, the said catch will come in contact with the projection l' on the collar l, and push the same around, thereby winding up the cord i' and drawing the beater back from the hay. The lower end of the pawl K will then come in contact with the incline m, and will be thrown out of connection with the collar l, when the beater C will be vehemently thrown against the hay by means of a weight, M, attached to the rocking-frame, (seen in fig. 2.) When the hay is pressed enough the beater is secured in place by two catches d' fitting into appropriate notches in the sides of the beater.

With this press I can press hay, hemp, and other articles with a smaller number of revolutions of the windlass than could heretofore be done. Furthermore, I combine, by means of the weight on the rocking-frame, the advantages of horizontal and vertical presses, and I save much labor by being enabled to place my press down upon the ground, whereby the hay need not be thrown to a height of from four to five feet into the press.

Having thus described my invention, I claim as new, and desire to secure by Letters Patent—

1. The arrangement of the drums f^1 and f^2 , clutch h' , ropes g^1 and g^2 , pulleys f and g^3 , lever G , and links b , for the purpose of operating the follower B , substantially as and in the manner herein shown and described.
2. I claim the arrangement of the collar i , rope i' , pulleys i'' , rocking-frame I , weight M , and link e , for the purpose of operating the beater C , substantially in the manner herein shown and described.
3. I claim the combination of the collar l , projection l' , and catch K with the incline m , substantially in the manner and for the purpose herein shown and described.

WILLIAM B. SMITH.
